UNITED STATES PATENT OFFICE

ALWIN G. STEINMAYER, OF MILWAUKEE, WISCONSIN, ASSIGNOR, BY MESNE ASSIGNMENTS, TO LINE MATERIAL COMPANY, OF SOUTH MILWAUKEE, WISCONSIN, A CORPORATION OF DELAWARE

FUSE

Application filed April 2, 1928. Serial No. 266,614.

This invention relates to certain new and useful improvements in fuses and refers more particularly to that type commonly known as expulsion fuses.

5 It is customary in fuses of this type to employ one tube to cover a voltage range of from 2300 to 6600 volts and heretofore this has been accomplished with considerable difficulty in that the relatively high voltages 10 require extremely fast volatilization of the fuse element whereas with voltages of a comparatively lower value it is essential that the speed of volatilization be materially reduced, to insure enough of the element being burned 15 away to prevent the possibility of current leakage and to this end it is desirable that the tube be of comparatively small internal diameter when the voltage is high so as to increase the speed of volatilization and larger, 20 when the voltage is relatively low so that the speed of volatilization is reduced.

Therefore, it is an object of this invention to provide a fuse of the character described which is so constructed as to be equally 25 adaptable for use with either low or high voltages.

Another object of this invention resides in the provision of a fuse of the character described in which the tube has a plurality of 30 inside diameters.

And a further object of this invention resides in the provision of a fuse of the character described in which the tube has a relatively small diameter for a portion of its 35 length and a larger inside diameter throughout the remainder of its length, the reduced section or point of initial rupture of the fuse element being positioned within the portion having the small diameter.

40 With the above and other objects in view which will appear as the description proceeds, my invention resides in the novel construction, combination and arrangement of parts substantially as hereinafter described 45 and more particularly defined by the appended claims, it being understood that such changes in the precise embodiment of the hereindisclosed invention may be made as come within the scope of the claims.

50 In the accompanying drawing, I have il-

lustrated one complete example of the physical embodiment of my invention constructed according to the best mode I have so far devised for the practical application of the principles thereof, and in which:

The single figure is a transverse sectional view taken through a fuse embodying my invention.

Referring now more particularly to the accompanying drawing, numeral 5 designates a tube of insulating material preferably bakelite or fibre having a bore 6 of relatively small diameter extending for approximately one fourth its length and a larger bore 7 extending throughout the remainder of its length. 65 A contact 8 is secured on the end of the tube having the smaller inside diameter and a second contact 9 is secured on the tube at a medial point, the contacts being electrically connected by a fuse element 10 and forming means by which the fuse is connected with an electric circuit, not shown.

The contact 8 is provided with an upwardly extended projection 11 which is centrally bored, as at 12 to register with the bore 6 and is externally threaded to receive a cap member 13, between the end wall of which and the outer face of the projection 11 the head of a substantially T shaped portion 14 formed by bending the adjacent end of the fuse element, 80 is impinged to thus electrically connect the element with the contact 8; the other end of the element being connected with the contact 9.

The contact 9 is provided with an annular flange 16 which is externally threaded to receive a collar member 17 and that portion of the contact extended beyond the flange 16 is taperingly reduced, as at 18. The collar member 17 has an inwardly extending annular flange 19, the peripheral wall or bore 20 of which is correspondingly tapered so that threading of the collar member onto the flange 16 causes the tapered faces 18 and 20 to approach each other. The fuse element 95 extends through the open end of the tube and is then directed back on itself, the end 15 thereof extending upwardly to be passed between the tapered faces 18 and 20 to be securely clamped therebetween and thus electrically 100

connected with the contact 9. The fuse element 10 is provided with the usual portion 21 of reduced cross sectional area which is located adjacent the contact 8 within the bore 6 so that upon an overload the initial rupture of the element takes place within the bore of smaller diameter, and if the voltage with which the fuse is being used is relatively high, the volatilization is sufficiently rapid due to the restricted area of the bore, thus preventing damage to the equipment, or the fuse itself. Likewise, if the voltage with which the fuse is used is relatively low, the larger diameter of the tube automatically compensates for the rapid volatilization which takes place within the smaller bore and permits the fuse element to burn away at a sufficiently low speed to insure the entire element being destroyed.

If desired, a tube 22 may be extended from the collar member 17 to enclose the lower end of the tube 5 and the upwardly directed portion or end 15 of the fuse element. It will also be understood that the tube 5 may be formed of two separate units or sections, one of smaller and the other of larger diameter.

What I claim as my invention is:

1. In an expulsion fuse of the character described, a tube having a bore of relatively small diameter extending throughout a portion of its length and a bore of greater diameter extending throughout the remainder of its length, said bore of greater diameter being unrestrictedly open to the atmosphere, contacts carried by the tube, and a fuse element positioned within the tube bores and electrically connected with the contacts.

2. An expulsion fuse comprising a tube having bores of different diameters and having one end unrestrictedly open to the atmosphere, a pair of contacts, and a fuse element within the tube and electrically bridging the contacts.

3. In an expulsion fuse of the character described, a tube having a bore of relatively small diameter and a bore of greater diameter, said bore of greater diameter being unrestrictedly open to the atmosphere, contacts carried by the tube, and a fuse element electrically connected with the contacts and positioned within the bores of the tube the fuse element having a portion of reduced cross sectional area, which is positioned within the bore of small diameter whereby initial rupture of the fuse element takes place within the bore of smaller diameter.

4. In an expulsion fuse of the character described, a tube having bores of different diameters, the bore of greater diameter being directly open to the atmosphere, a contact connected with the tube adjacent the bore of smaller diameter, a second contact adjacent the other end of the tube, and a fuse element having one end connected with the first mentioned contact and its other end passed out-

wardly through the open end of the tube and electrically connected with the second contact, the fuse element having a portion of reduced cross sectional area disposed within the bore of smaller diameter whereby the volatilization of the fuse element is rapid at the time of initial rupture and becomes comparatively slower as the element burns away.

In testimony whereof I have hereunto affixed my signature.

ALWIN G. STEINMAYER.
